FLASHLIGHT ATTACHMENT FOR
PHOTOGRAPHIC CAMERAS

Wilhelm Stein, Wetzlar (Lahn), Germany, assignor to Ernst Leitz, G. m. b. H., a corporation of Germany

Application July 23, 1952, Serial No. 300,372

Claims priority, application Germany
September 4, 1951

3 Claims. (Cl. 67—31)

1

This invention relates to improvements in flash attachments for photographic cameras. Such attachments generally consist of a holder which is detachably mounted upon the camera and the holder in turn supports a battery, lamp and reflector. The supporting element itself is arranged to support an Edison lamp with a screw threaded base or a push in lamp with a base provided with projecting pins which enter corresponding recesses in the lamp socket. Existing devices of this sort require a separate part to fit the type of lamp used. The separate part is then secured in the lamp support.

The object of this invention is to provide an improved flash attachment of the type referred to. The invention is embodied in a device which includes a reversible lamp connecting sleeve with coaxially arranged sockets at opposite ends adapted to receive two different types of lamps. One end of the sleeve forms a socket for an Edison lamp, the other end of the sleeve forms a socket for a push-in lamp.

The device has the advantage that by the mere reversing of the lamp sleeve either one or the other lamp may be used. The carrying about of a separate part is done away with. The sleeve is in known manner clamped to the battery housing and the lamps are likewise clamped to the sleeve by springs. When the springs are released by the pressing of suitable operating buttons, the lamps are released and automatically ejected. The holder referred to above is pivotally connected to the camera by a clamping screw so that the reflector may be adjusted for different distances of the object. This arrangement also facilitates transport of the device.

Accordingly the invention is embodied in a flash attachment as hereinafter described and claimed and as illustrated in the accompanying drawings in which

Fig. 1 shows a camera with the flash attachment thereon, a portion of the reflector being removed.

Fig. 2 is wiring diagram.

Fig. 3 is an exploded view showing the upper part of the battery casing in section, and above it, the reversible socket sleeve with a push in lamp in position.

Fig. 4 is a similar view but shows the battery casing in side view, and above, it also in side view, the reversible socket sleeve with an Edison lamp in position.

Fig. 5 is a sectional view of the socket sleeve.

Fig. 6 is a sectional view on the line 6—6 through the Edison socket in Fig. 5.

2

Fig. 7 is a sectional view on the line 7—7 through the push-in socket in Fig. 5.

Figs. 8, 9 and 10 are detail sectional views of the means for securing the reversible socket sleeve to the neck of the battery housing, Figs. 8 and 9 being sectional views on the lines 8—8 and 9—9 of Fig. 10, respectively.

Fig. 1 illustrates a camera 1 upon which a flash holder is detachably mounted. The holder comprises the brackets 2 and 3. The latter are pivotally connected by a clamping screw 6. The bracket 2 may be detachably secured to the camera by the usual tripod connection, not shown. Fig. 2 shows the electric flash circuit with a battery casing 4 and the wires 7 connecting the battery circuit with the flash synchronizing switch 8.

The battery casing 4, Figs. 3 and 4, has at its top a neck 10 adapted to receive the reversible socket sleeve 11 with a socket 12 for an Edison lamp and a socket 13 for a bayonet type lamp. Within the neck 10 there is a support 16 for a spring pressed axially movable contact 14 which is pressed normally outward by a spring 15. In the ends of the sleeve 11 are openings 17, Figs. 6 and 7, through which the contact 14 projects into the sleeve. The Edison lamp socket 12 is secured upon the one tubular end 19 of the reversible sleeve 11. The bayonet type socket is secured upon the opposite tubular end 22 of the sleeve as shown in Fig. 5.

The reversible sleeve 11 is secured to the battery casing by the following means. The neck 10 has two diametrically oppositely located openings 10a with open mouths 10b, Fig. 10. The sleeve 11 contains a spring 26 with two buttons 25, Figs. 5, 8 and 9, adapted to enter and be seated in the said openings 10a through the mouths 10b. Each button has a stem 25a which can pass through the mouth 10b into the opening. Each button also has a base 25b which fits the opening 10a.

In mounting the sleeve 11 within the battery casing neck 10, the buttons 25 are pressed inwardly against the force of the spring 26. The button stems 25a then pass down into the openings 10a and by releasing the buttons they are pressed outward by the spring 26 and become fixed in the openings 10a thereby finally supporting the sleeve 11 on the battery casing neck 10.

The Edison socket 12, Figs. 5 and 6, is provided with a ring formed spring 18 having a straight portion 18a with a nose 18b. The parts 18a and 18b project inwardly into the socket through an opening 19a in an inner guiding sleeve 19. The

spring carries buttons 20. The flat portion 18a and the nose 18b of the spring engage the screw thread on the base 9 of an Edison lamp when it is inserted in the socket 12 and thus secures the lamp in its socket. When the buttons are pressed inwardly, the spring 18 is flexed so that it becomes disengaged from the lamp. When the lamp is inserted into the socket and makes contact with the contact 14, the spring 15 is collapsed. When the spring 18 releases the lamp from the socket, the spring 15 expands and ejects the lamp from the socket.

The bayonet lamp socket 13, Figs. 5 and 7, contains a ring formed spring 21 with a flat portion 21a and a hole 21b projecting inwardly through an opening 22a in a guiding sleeve 22. The latter has a recess 22b diametrically opposite the hole 21b. When a bayonet lamp base 23 is inserted into the push-in socket 13, the usual pins 23a and 23b on the lamp base engage the hole 21b in the spring 21 and the recess 22b directly opposite whereby the spring 21 is momentarily flexed outwardly and the lamp base 23 is then held in position by the spring 21. By pressing inwardly upon a button 24 the spring 21 is disengaged from the lamp base 23 and the lamp is then ejected by the spring 15. The lamp base is secured in the socket 13 by a push in movement. The lamp is ejected when the spring is flexed outwardly by a pressure on the button 24.

The connecting sleeve 11 may be placed upon the battery casing with either one of the lamp sockets uppermost, Figs. 3 and 4. In either position the sleeve is reversibly mounted by the aforesaid means described in connection with Figs. 8, 9 and 10. If an Edison lamp is to be used, the Edison socket 12 is uppermost. If a bayonet lamp is to be used the other socket 13 is uppermost. In either case the lamps are held in the sockets by the springs 18 or 21, respectively. When the buttons 20 are depressed, the Edison lamp is released and thereupon ejected by the spring 15. When the button 24 is depressed, the bayonet lamp is released and then likewise ejected. When the buttons 25 are depressed, the sleeve is released from the battery neck and may then be reversed.

The invention is susceptible of changes and modifications and all such changes and modifications are claimed as come within the principle of the invention and the scope of the appended claims.

I claim:

1. A flash attachment for photographic cameras in combination a battery casing, a spring pressed lamp ejector in said casing, a lamp supporting sleeve having a tubular portion at each end, a lamp socket supported in each of said tubular portions of said sleeve in coaxial alinement therein, means in each of said tubular portions and the socket therein for receiving and ejectably supporting a lamp therein, means in said sleeve

and battery casing for detachably and reversibly supporting said sleeve upon said casing with one of the said tubular portions and the socket therein in position to receive the lamp to be inserted therein in automatic operative relation with said lamp ejector to eject the lamp after use.

5 2. A flash attachment for a photographic camera comprising a holder, a battery casing in said holder, an electric circuit in said casing including and exposed movable contact, a lamp supporting sleeve having a tubular portion at each end, a lamp socket supported in each of said tubular portions in coaxial alinement therewith, springs in said sockets for releasably retaining lamps in the sockets in automatic contact with said movable contact when lamps are inserted in the sockets, means in said sleeve and said battery casing for detachably and reversibly mounting the sleeve upon said battery casing 10 whereby to support a lamp inserted in either of the said two lamp sockets in operative position upon the casing, buttons accessible from the outside to actuate the said socket springs to release the lamp in the socket and a spring for actuating 15 said movable contact to cause the latter to eject the lamp from the socket when said buttons have been operated to release the lamp and means for detachably supporting said holder upon the camera.

20 30 3. A flash attachment for a photographic camera comprising a holder arranged for mounting upon the camera, a battery casing in said holder terminating in an exposed tubular neck, an electric circuit in said casing including an 35 exposed movable contact within the said neck, a lamp supporting sleeve having a tubular portion at each end, a lamp socket in each of said sleeve tubular portions in coaxial alinement, spring 40 pressed buttons in said sleeve and cooperating openings in said neck to receive said buttons for detachably and reversibly securing the sleeve upon said neck, a spring in each of said sockets for releasably retaining a lamp therein in automatic contact with said movable contact when a 45 lamp is inserted in the socket with said sleeve secured in said neck, buttons accessible from the outside to actuate said socket springs to release the lamp from the socket and a spring for actuating said movable contact to cause the latter to eject the lamp from the socket when said buttons have been operated to release the lamp and means for detachably supporting said holder upon the camera.
